UNITED STATES PATENT OFFICE.

ARTHUR M. TAYLOR, OF KEUKA PARK, NEW YORK.

BASKET-HANDLE-NAILING MACHINE.

1,151,307.

Specification of Letters Patent. Patented Aug. 24, 1915.

Application filed October 7, 1910, Serial No. 585,839. Renewed March 20, 1915. Serial No. 15,902.

To all whom it may concern:

Be it known that I, ARTHUR M. TAYLOR, a citizen of the United States, residing at Keuka Park, in the county of Yates and 5 State of New York, have invented certain new and useful Improvements in Basket-Handle-Nailing Machines; and I do hereby declare the following to be a full, clear, and exact description of the invention, such as 10 will enable others skilled in the art to which it pertains to make and use the same.

This invention relates to nailing machines; especially adapted for nailing handles to baskets and embodies improvements hereinafter fully set forth and claimed.

The main object of this invention is to provide means for handling and securing the basket body, providing means for clamping the basket body, said clamping means 20 acting as an anvil to support the upper edges of the basket body and to clench the fasteners as they are driven home through the handle and into the body.

Another object of this invention is to provide for the feeding of the nails, tacks or fasteners, one at a time, to hammers and into position to be acted upon by the hammers and driven home.

Other objects of this invention will appear in the specification hereinafter.

This invention consists in parts and combination of parts, all of which will be hereinafter fully set forth and claimed.

In the drawings, Figure I, is an isometric view of the machine as a whole, illustrating one type of construction in which the invention is embodied. Fig. II is a plan view of the table with the nail or tack hopper removed, illustrating the plunger operating mechanism and the combined anvil and clamp. Fig. III, is an enlarged detail view in section illustrating the manner in which the fasteners are fed and supported while being driven. Fig. IV, is an enlarged view 45 of the fastener or tack supporting trough showing the end of the plunger and one end of the feeding tube, and also illustrating the yielding tack supporter. Fig. V, is a detailed view showing the back piece for 50 supporting and gaging the position of the basket body. Fig. VI, is a detailed front view in elevation of the combined anvil and clamp piece.

The machine embodied in the invention is

adapted to fasten handles to baskets. The 55 different parts are illustrated as at the present time appear especially applicable for this work, but it is not intended that the exact combination or structural features shall be considered essential as the same 60 may be modified without departing from the invention.

In the drawings submitted herewith the operative mechanism of the machine is mounted on a stand comprising four legs 65 1, 1, 1, 1, surmounted by a table 2, on which in turn is mounted four hoppers 3, 3, 3, 3, supported by uprights 3', 3', secured to the table 2. The hoppers 3, 3, 3, 3, are adapted to hold tacks, nails or other proper fasteners 70 which are fed through suitable arranging chutes 4, 4, 4, 4, and are delivered into tubes 5, 5, 5, 5, one at a time by means of check slides 6, 6, 6, 6, operated at each action of the machine through means of suitable connections formed on the pivoted lever arms 13. Thus far the construction may be of 75 any suitable type adapted for the purpose.

The delivery end of the tubes 5, 5, 5, 5, (see Figs. III and IV) lead into V shaped 80 troughs 18, and are provided with a side slot 5' for the exit of the nail, tack or fastener 19' delivering its point properly and onto the hammer or plunger 10, which when retracted allows the nail to drop into the bottom of the 85 V shaped trough 18 and into position to be driven by the plunger 10. In order to properly present the point of the nail or tack 19' and guide it in driving, a yielding support 20, consisting of a bell crank shaped weighted 90 lever and having a notch 20' is provided for this purpose, the notch 20' being inclined upwardly and outwardly as shown in Fig. III so that as the nail 19' is driven home the support will yield to the head of the nail. 95 The plungers or hammers 10 are mounted in housings 10' the same being preferably formed in one piece with the trough 18. The mechanism for operating the plunger or hammer 10 is shown in Figs. I and II 100 and comprises a toggle-jointed lever 13, the respective arms of which are pivoted at their ends to the pivoted lever arms 13' which in turn are pivotally connected to the central portion of a spanner bar 17—17 and thus 105 as the toggle arms 13—13 are opened or closed the plungers 10, 10, 11, 11, are projected against the nail 19' or are retracted

to allow of the dropping of another nail 19. The toggle arms 13, 13 are operated by means of a connecting rod 14, which in turn is pivotally attached to a rod 15, extending upward from a treadle 16 and braced by a brace rod 15' also secured to the treadle 16 which in turn is hinged to a cross bar 16'' and has a foot piece 16'. Now as said foot piece 16' is depressed the toggle arms 13, 13 open and drive the plungers or hammers 10, 10, 11, 11, and when released the spring 24 acting on treadle 16 closes the toggle arms 13, 13, and the plungers or hammers are retracted. The above clearly sets forth the 15 nailing mechanism as illustrated and also the tack or nail presenting mechanism and their operations.

It remains to set forth the basket holding means which is shown more clearly in Figs. 20 I, II, V and VI, and comprises an upright back piece secured to the table 2 to the rear of an opening 7' formed in the front position of said table 2, to admit the basket body A (see Figs. I, and II) and handle C. The 25 basket piece 7 is provided with an adjustable support 9, carrying clamp arms 8, 8, to gage the position of the basket body and retain it in place, (see Fig. V, dotted lines). The bottom B of the basket body rests 30 against the back piece 7. In order to hold the basket body against the back piece 7, a swinging anvil clamp block 21, is provided. This clamp block and combined anvil 21, is mounted at the upper end of a vertical horizontally swinging lever 22, hinged at its 35 lower end 22' to a bar 1', of the inclined frame, and is attached to a spring 24. A bell crank 23 engages the lower end of the lever 22 and throws it outward by depressing the treadle 23' to allow of the basket body being inserted in the opening 7' and against the back piece 7 and then the treadle 40 connected to the bell crank 23 is released.

As illustrated in Fig. VI, of the drawings 45 and as also shown in Fig. I, the anvil block and clamp, (the same being formed of metal) is provided with two extending lugs 21', 21' at the lower ends, the object of these lugs being to form a rest for the handle C, when it is inserted in the opening 7' and to hold said handle contiguous to the body of the basket A, gaging the handle centrally of the body. It will also be noticed in Fig. II, of the drawings that this combined clamp 50 and anvil block is provided with projections b, b, at either side, which are adapted to engage the upper edge of the basket body contiguous to the position of the handle C. The main portion of the anvil block is so 55 formed as to fit tightly or securely within the basket body, thus forming an anvil against which the nails or fasteners that attach the handles to the body may be clenched, and suitable recesses such as a, a, 60 may be provided in the body of the anvil

block for this purpose, viz. of turning the points of the nails or fasteners back into the basket body.

Now having set forth the construction, and in a general way, the operation of the 70 machine as a whole, and of the different mechanisms embodied therein, it seems but necessary to outline the operation of fastening the handles to the baskets. The first operation is to throw the anvil 21 outward by 75 means of a treadle 23' and against the tension of the spring 24; this allows of the insertion of the body A, of the basket against the back piece 7, resting within the arms 8, 8, on the rest 9, the same being so adjusted 80 that the central portion of the basket is approximately level with the projections 21', 21'. The next operation is to release the treadle 23' when the spring 24 throws the anvil clamp 21 against the upper edge so 85 as to bring the projections b, b, against the upper edge of the basket body, forcing it back against the back-piece 7, and retaining it in this position. The handle C, resting upon the projections 21', 21', is then put in 90 position outside the basket body as shown in Fig. II, and the foot piece 16', which operates a treadle 16, is depressed straightening the toggle arms 13, 13, and bringing the four plungers 10, 10, 11, 11, toward the basket body and handle, driving the fasteners at the bottom portion of the basket through the handle and into the bottom portion of the basket and at the upper portion of the basket, through the handle and into the 95 body of the basket and against the anvil block and clamp 21, thus clenching the fasteners at this point. This action is repeated and at each repetition of this action the check slides 6, 6, pass a tack or fastener 19 100 (see Fig. III) which passes through the tube 5, rests upon the plunger 10, until said plunger is retracted, then dropping to the bottom of the trough 18, ahead of the plunger 10, and in position to be driven by said 105 plunger upon the depression of the treadle 16.

It will be noted that the spring 24 is attached respectively at one end to the treadle 16, and at its opposed end to the swinging 110 bar 22. This construction first obviates the necessity of using more than one spring for this purpose, and secondly as the treadle 16 is depressed, the clamp action of the lever 22 and its anvil block and clamp 21, is increased. 115

As hereinabove stated in illustrating and setting forth this invention, I have confined the same to a machine for securing certain handles to certain types of basket bodies and have also set forth details of construction which are considered as best adapted for this purpose, but I do not wish to be limited in any respect to these details or to this precise assemblage or operation of the parts, 120 125 130

inasmuch as the same may be modified and departed from and still contain the essentials of the invention.

What I claim is:

1. A machine for securing handles to basket bodies comprising means for retaining and clamping the basket body in position, means for retaining the handle in proper position relative to the body, hammers located so as to operate from both sides of the body and operating to drive fasteners through said handles and means for delivering fasteners to said hammers.
2. A machine of the type set forth comprising a body support for the basket, a handle support to retain the handle in proper position relative to the body, a clamping device adapted to hold the body in position, said clamping device adapted to be released for the removal and replacement of a basket body, means for releasing the same and means for securing the handle to said basket body, substantially as set forth.
3. A basket handle nailing machine of the type set forth comprising means for securing handles to basket bodies, a rest for the basket body, and a swinging anvil for keeping said basket body in position, said

anvil acting as a means for holding said handle in position for securing the same to the basket body, all substantially as and for the purpose set forth.

4. A machine of the type set forth comprising means for securing handles to basket bodies, a rest into which fits the said basket body, and a swinging anvil for holding said basket body in position in said rest, said anvil formed so as to clench the fasteners; all substantially as and for the purpose set forth.

5. A basket handle nailing machine of the type set forth comprising means for securing handles to basket bodies, a rest for the basket body, and a swinging anvil having portions for keeping said basket body in position, said anvil acting as a means for holding said handle in position for securing the same to the basket body, all substantially as and for the purpose set forth.

Signed at Keuka Park in the county of Yates and State of N. Y. this day 22 Aug. 1910.

ARTHUR M. TAYLOR.
